UNITED STATES PATENT OFFICE

WILFORD R. SPROUL, OF CHICAGO, AND HUGO LAYER, OF WINNETKA, ILLINOIS, ASSIGNEES TO E. W. SPROUL CONSTRUCTION COMPANY, OF CHICAGO, ILLINOIS, A CORPORATION OF ILLINOIS

METHOD AND APPARATUS FOR CONCRETE WALL CONSTRUCTION

Application filed March 26, 1928. Serial No. 264,620.

This invention relates to the construction of concrete buildings, particularly to the construction of the type of buildings wherein the floors of concrete slab construction are carried on a reinforced concrete frame which is enclosed within a monolithic concrete wall. Such a type of construction is sometimes employed in cold storage buildings and the like, wherein it is desired to insulate the enclosing 5 wall against transmission of heat.

The invention has to do with method and means for the construction of the enclosing wall, or curtain wall as it is sometimes called, with the use of slip forms. As will be understood, slip forms are of a type in which the form panels, which constitute the mold surfaces between which the concrete is poured and shaped in the building up of the wall, are arranged so as to be elevated from time to 10 time in the proper position to continue the mold cavity on upwardly from portions of the wall already poured and set, to receive additional pourings of concrete.

A general object of the invention is the 15 provision of improved method and means for the construction of curtain walls in the desired association with frame and floor construction which is already in place.

A more particular object is the provision 20 of such method and means whereby the curtain wall may be constructed accurately and rapidly by the employment of slip forms, without involving complications in the manipulation or construction of such forms.

Still another object is the provision of such 25 method and means whereby the curtain wall may be constructed with suitable provisions for installation of insulating material.

Other and further objects will be pointed 30 out or indicated hereinafter, or will be apparent to one skilled in the art upon an understanding of the invention or its employment in practice.

In the accompanying drawing forming a 35 part of this specification we illustrate apparatus and construction wherein the invention may be embodied and by which it may be practiced, but it is to be understood that these are presented for purposes of example only, 40 as the invention is not limited in embodiment

or use to the particular forms of apparatus herein shown and described.

In said drawings

Fig. 1 represents an elevational view of a portion of a building frame with form guides 55 in place;

Fig. 2 represents a transverse elevational view of an embodiment of our improved slip form in association with a portion of the building construction, and

Fig. 3 is a horizontal sectional detail taken on substantially line 3—3 of Fig. 2.

In the construction of buildings with monolithic concrete walls, it is frequently desirable to erect the frame and place the floors 60 before building the enclosing wall. Such a frame is illustrated, for example, in Fig. 1 wherein the portions C represent columns of the building frame and the portions designated F represent floor parts which are carried on the columns. In the erection of monolithic concrete walls, the employment of slip forms gives certain very important advantages in the saving of time, material and labor. The employment of slip forms 65 and a realization of their usual advantages, in the construction of such walls in conjunction with frames and floors already in place, has presented a difficult problem, involving various considerations not encountered in the 70 erection of such walls in advance of the placing of the associated floors. The present invention provides a solution of this problem in such fashion that the customary advantages of operation with slip forms are availed 75 of.

For a description of the method and the apparatus employed, resort will be had to the example illustrated in the accompanying drawing. We will assume a situation in 80 which the building frame portions consisting of the columns C and the floor portions F including the beams and slabs, have been erected to a suitable height, and it is desired to close this frame portion with a curtain 85 wall which is to be heat insulated. In the forming of the floor slabs, holes 10 are provided in the slabs at suitable intervals along their outer margins, same being formed, for example, by the insertion of short sections of 90 95 100

pipe in the slab forms before the floors are poured. As a preliminary to the erection of the wall, vertically running form guides 11 are arranged at the desired horizontal intervals between the floors and at the outer margins thereof, said guides being lined up vertically from floor to floor. Each of these guides has a vertical guide strut 11^a carrying brackets 11^b at the ends. These guides are wedged firmly between adjacent floors or floor beams by wedges 12 and are connected by clamping rods 14, which are passed through the holes 10 and drawn up tightly by nuts 15 to clamp the vertically aligned guides tightly against the slabs or beams. The slip forms comprise a plurality of frames made up of the vertical members 16 which are rigidly connected in parallel relationship and carry the form panels 17, the handling platform or runway 18 and the jack screws 19. The form panels 17 are spaced apart transversely, to afford the mold cavity in which the concrete is poured to form the wall W. The jack screws are adapted for cooperation with clamps 20 which may be affixed to the jack rods 21 that extend vertically in the wall and constitute the supports on which the frames and their carrying portions may be elevated from time to time by operation of the jack screws. The frames are adapted to have lateral support and guidance on the guide members 11, such as to maintain the forms in the desired vertical position against the weight of the handling platform. Wear strips 22 are carried by the frames for bearing cooperation with the guides. In order to hold the frames in the desired alignment with the guides and to support them above their points of support on the jack rods, the frames are provided with movable guide yokes which include the jaws 24 which are pivotally connected to the frames at 24^a and are adapted when in their extended position to straddle the guide struts 11^a. The guide yokes are maintained in cooperation with the guide struts by bolts 24^b which are removable and which carry rollers 24^c adapted to ride on the inner side of the guide strut.

The slip forms being thus associated with the guides and the form panels being thus maintained in the desired position, concrete is poured in the mold cavity and suitably distributed and allowed to set to the desired firmness. Thereupon the forms are elevated to the desired extent by manipulation of the jack screws, to extend the mold cavity upwardly from the portion of the wall which has been poured. Operation continues in this fashion, so that the wall is gradually built up by addition of new pourings of concrete at the top. As one of the guide yokes is brought to a position near the upper end of its cooperative guide 11, the bolt 24^b is withdrawn, and the guide jaws swung back

to a position where they clear the margin of the floor, as illustrated by the next to the uppermost guide jaws 24 in Fig. 2. Upon further elevation of the form to a position where this guide yoke may be engaged with the next guide strut, the jaws are swung out again and the bolt and roller replaced, as illustrated by the topmost guide yoke in Fig. 2. Thus the upward progress of the forms is continued throughout the desired height of the building, the forms at all times being afforded the proper support and guidance to insure the wall being built up in the desired plumb position and in the desired relationship to the frame and floors. The space S afforded between the inner surface of the wall W and the margin of the floor is left for the reception of insulating material, such as slab cork, or other desired inner surfacing for the wall. Guides 11 which have been passed by the forms, may be removed and reinstalled above the forms. The holes 10 may be either closed by grout or may be utilized for the placement of tying connections between the wall and the floors.

By employment of the method and means above described, the curtain wall may be erected rapidly and accurately with employment of slip forms operated in the customary fashion. The guides 11, being made in standard lengths, may be employed repeatedly on different jobs.

What we claim is:

1. A method of building monolithic concrete walls in association with previously erected building frame structures, which comprises securing vertically extending form guides to the frame structure one above another so as to extend across successive stories of the building, guiding and supporting vertically movable wall forms on said guides in proximity to the building frame, elevating the forms from one guide to another, and placing successive deposits of concrete mixture one on top of another within the wall forms.

2. A method of erecting a concrete curtain wall in association with previously constructed floors, which comprises securing vertically running form guides between the floors, one above another, supporting and guiding a vertically shiftable wall form on said form guides, elevating the wall form by stages, and placing pourings of concrete mixture one on top of another within the wall form.

3. Apparatus for erecting concrete walls in association with previously erected building frames, which comprises, in combination, vertically shiftable slip forms for receiving the wall pourings, form guides adapted for guiding cooperation with the forms, and means for connecting said form guides to the building frame.

4. Apparatus for erecting concrete walls

in association with previously erected building frames, which comprises, in combination, vertically shiftable slip forms for receiving the wall pourings, form guides adapted for guiding cooperation with the forms, and means for connecting said form guides to the building frame in vertical alignment.

5. Apparatus for erecting concrete walls in association with previously erected building frames which comprises, in combination, vertically shiftable slip forms for molding the wall, form guides, means for connecting the form guides to the building frame to afford vertical form guides and means affording supporting and guiding connection of the form to the guides.

6. Apparatus for erecting concrete walls in association with previously erected building frames comprising, in combination, a vertically shiftable wall form, form guides, means for connecting the form guides to the building frame, and guiding connections between the form and the guides, said guiding connections being shiftable to clear portions of the building frame during elevation of the form.

7. Apparatus for erecting concrete walls in association with previously erected building frames, which comprises, in combination, a vertically shiftable wall form, means for elevating same, form guides, means for connecting the form guides to the building frame, and a plurality of vertically spaced guiding connections for holding the form to the guides, said guiding connections shiftable to clear portions of the frame during elevation of the form.

8. Apparatus for erecting concrete walls in association with previously erected building frames comprising, in combination, a slip form for molding the wall, means for elevating the slip form, form guides, means for connecting the form guides to the building frame, guiding connections at one side of the form for holding it in association with the guides, and a handling platform at the other side of the form.

9. Apparatus for erecting concrete walls in association with previously erected building floors comprising, in combination, a slip form for molding the wall, form guides adapted to extend vertically between the floors, means for securing said guides in vertical alignment between the floors, and connecting members for securing the form to the guides for vertical travel along the latter.

In testimony whereof we have hereunto
60 subscribed our names.

WILFORD R. SPROUL.
HUGO LAYER.
